WEAVING TUFTED FABRIC

John Henry Moore, Methuen, Charles Edward Jewett, North Andover, and Roy Edwin Burdett, Lawrence, Mass., assignors to Pacific Mills, Lawrence, Mass., a corporation of Massachusetts

Application December 27, 1937, Serial No. 181,778

6 Claims. (Cl. 139—116.5)

This invention relates to the production of tufted woven fabric and particularly to the cutting of the floating threads on the fabric to permit their formation into tufts or the like.

5 In the production of a tufted woven fabric threads of a character intended to form the tufts are woven into the fabric with either the warp or the filling threads and are floated for a considerable distance on the surface of the fabric.

10 The floating threads are then cut and given the proper finish to produce the desired tufted effect.

Heretofore the operation of cutting the floating threads has been separate from the weaving process and difficult and expensive to perform because of the difficulty of severing the floating threads with the accuracy required.

An object of the present invention is to sever the floating threads as a part of the weaving operation.

20 A further object of the invention is the provision of means associated with the loom which operates automatically to sever the floating threads after they have been incorporated in the fabric before the fabric is wound onto the take-up roll.

25 When the floating threads are woven into the fabric with the filling threads the cutting of the floating threads is accomplished by a series of stationary knives which are disposed close to the upper face of the moving web and pass under the floating threads and thereby sever them by the movement of the web. When the floating threads are woven in with the warp threads the series of knives are periodically reciprocated to move under the floating threads to sever them, the movement of the knives being effected under control of the pattern chain or the equivalent. Such constructions comprise further objects of the invention.

Ordinarily the woven fabric advances with each 40 lay of a filling thread and when the floating threads are woven with the filling threads there will be unwoven sections underlying the floating threads. Hence another object of the invention is in the provision of means for stopping the advance of the fabric during the laying of the floating threads so that the fabric is closed under the floating threads.

A further object of the invention is in the provision of stop mechanism for the take-up roll 50 rendered operative to disable the take-up roll concurrently with the service positioning of the floating thread shuttle and being operative to again start the take-up of the fabric concurrently with the moving of the floating thread shuttle out of service position.

A further object of the invention is generally to improve upon the weaving of tufted woven fabrics and mechanisms for severing the floating threads.

Fig. 1 is a front elevation of a loom embodying 5 the present invention and wherein the floating threads are woven in the fabric with the filler threads.

Fig. 2 is a detail illustrating the mechanism controlling the operation of the web take-up. 10

Fig. 3 is a sectional detail taken generally along line 3—3 of Fig. 1, and illustrating the relative position of a thread-cutting knife with respect to the breast beam and the take-up mechanism.

Fig. 4 is a plan view of a knife. 15

Fig. 5 is an enlarged view of the knife of Fig. 3 and illustrating the manner in which the floating threads are moved onto the knife.

Fig. 6 is a plan detail of a section of fabric illustrating the severed floating threads. 20

Fig. 7 is a plan view partly broken away of a loom wherein the floating threads are woven in the fabric with the warp threads.

Fig. 8 is a front end detail of the loom of Fig. 7.

Fig. 9 is a front elevation of a knife for severing the floating warp threads. 25

Fig. 10 is a side elevation of the knife of Figs. 8 and 9, and illustrating the manner in which the knife passes under and in contact with the floating threads. 30

In the construction illustrated in Figs. 1 through 5 the tuft-forming or floating threads are woven in the fabric with the filling threads. The loom for the purpose is more or less the usual loom having the harnesses 12 operated by the usual jack levers 14 which are reciprocated by the head mechanism 16 under control of the pattern chain 18. The loom is of the multiple shuttle type having the plural shuttles contained in a carrier 20 which is selectively raised and lowered 40 to move the shuttles into active position by a chain 22 controlled by a second pattern chain 24. The woven fabric passes over a breast beam 26 and around and between take-up rolls 28 and 30, see Figs. 1 and 3, and is wound upon a winding shaft 32. 45

The aforesaid rolls 28, 30 and 32 are driven by means including a worm gear 34 and a worm 36 fixed to a drive shaft 38 extended longitudinally of the machine at one side thereof. The shaft 50 38 at the side end of the loom is connected through pinion gears 40 with a short shaft having a bevel gear 42 fixed thereon and driven through the take-up reversing mechanism which includes a pair of bevel gears 44 and 46 fixed to 55

a sleeve 50 slidably axially on but keyed for conjoint rotation with a vertical shaft 52 that extends upwardly in a manner not shown, to operate the head mechanism 16. The shaft 52 is 5 driven from the drive shaft 54 by a pair of mating bevel gears 56. A helical compression spring 58 encircles the shaft 52 and normally urges the sleeve 50 in a downward direction to effect engagement between the upper sleeve gear 46 and 10 the bevel gear 42 so as to operate the take-up mechanism in the normal forward direction of movement of the web. The usual reversing arm 15 57 has a pin 60 that is disposed under a shoulder 62 of the lower gear 48 whereby to enable the sleeve to be raised to disengage the upper sleeve gear 46 from the bevel gear 42 and to bring the lower sleeve gear 48 into engagement with said bevel gear to effect a reversal of movement of the web in the usual manner.

20 When the floating threads are woven into the fabric with the filling threads it is desirable to arrest the advance of the woven fabric during the introduction of the floating threads so that the fabric will present a woven appearance under 25 the floating thread sections. For this purpose the floating thread preferably is contained in the lowermost shuttle and the position of the shuttle carrier is utilized to operate the reverse mechanism to render inoperative the take-up 30 mechanism.

For this purpose the lower end part of the sleeve 50 below the reversing arm 57 carries a collar 64 which has a projecting pin 66 engaged with an arm 68 fixed to a rod 70 which is vertically and axially movable in guides 72 and so arranged that upward movement of the rod acting through the pin 66 and collar 64 raises the sleeve 50 to disconnect the upper sleeve gear 46 from the gear 42, the movement, however, being 40 insufficient to move the lower sleeve gear 48 into engagement with the gear 42. The rod at its upper end part has an arm 74 provided with a projecting pin 76 that overlies a laterally projecting roller 78 of a pivoted filling indicating 45 lever 80 connected through a strap 82 with the shuttle carrier chain 22. The lever 80 thus rises and falls with the shuttle carrier and is so arranged as to engage the pin 76 and raise the pin and the shaft 70 when the shuttle carrier is 50 raised to position the lowermost floating thread shuttle in operative position, thereby to disconnect the take-up mechanism from the drive shaft 52. Consequently the fabric remains stationary during the in-weaving of the floating 55 threads. When the shuttle carrier drops under control of the chain 24 to throw in a regular filling thread the spring 58 operates to re-engage the upper gear 46 with the bevel gear 42 to operate the take-up mechanism again to advance 60 the web. The lay operates to close the weave under the floating threads at the time the web is stationary.

The floating filler threads 84, Figs. 1, 3 and 6, span a considerable number of warp threads on 65 the top face of the fabric. They also underlie a considerable number of warp threads. Preferably the underlying floating threads are caught to the woven fabric, or interwoven with two or three warp threads as indicated at 86, midway 70 between the surface floating threads so as to anchor the threads to the fabric after they are severed. The floating threads can be interwoven with the fabric in any desired pattern as determined by the setting of the pattern chain 75 18 to form a regular repeated pattern.

In accordance with the present invention mechanism is provided for automatically severing the floating threads accurately either in the middle thereof or in some other location as determined by the nature of the tufts or design desired. The severing mechanism comprises a bar 88 extended horizontally in front of and close to the vertical pass of the web between the breast beam 26 and the take-up roll 28, the bar being fixed at its ends in supporting brackets 90 10 attached to the breast beam beyond the selvage edges of the web.

The bar 88 carries a plurality of cutter elements each comprising a feeler rod 92, see especially Figs. 4 and 5, which is inclined upwardly 15 and rearwardly toward the fabric and is longitudinally adjustably secured by a set screw 94 in a chordal passage in a collar or knife holder 96 slidably mounted on the bar 88 and fixed thereto in any angular and axial adjustment thereof by a set screw 98. The feeler rod 92 is flattened at its forward end to provide a thin edge 100 and a flat under-surface 102 which rides upon or close to the face of the fabric. The feeler rod behind the edge 100 is provided with an 20 standing thin knife blade 104 having a sharp inclined edge 106. With this arrangement as the web passes downwardly the floating threads 84 25 pass over the edge 100 and onto the feeler rod 92 and are raised into loop-formation and move 30 upwardly on the rod and onto the knife edge 106 by which they are severed. Fig. 6 illustrates a section of the web with the severed floating threads 84. There are as many cutting elements 35 as there are bunches of floating threads distributed crosswise of the fabric. By properly positioning the cutting elements lengthwise of the supporting bar 88 the bunches of floating threads can be severed accurately wherever desired.

In the modification illustrated in Figs. 7 through 9, the floating threads are woven in the fabric with the warp threads, the floating threads being laid in with certain of the warp threads. That is to say, a floating thread is superposed over a regular warp thread so that the floating threads do not displace any warp threads. With this arrangement the fabric shows an unbroken weave under the floating sections of the threads. The floating threads are controlled by separate 50 harnesses 108 and in this instance a single shuttle is all that is necessary, although multiple shuttles may be employed where necessary to produce a desired pattern or character of woven fabric. Multiple shuttles, however, are not required to produce the tufted fabric. With this modification the arrangement of the floating sections of the floating threads can be anything desired as, for instance, the same as illustrated in Fig. 1, where the floating sections are arranged in rows and the sections in one row are staggered with respect to the sections in the next row.

The cutting mechanism for the floating sections in this modification comprises a pair of parallel bars 110 and 112 disposed above the horizontal pass of the woven fabric on the breast beam 114. Each bar carries a plurality of cutting elements. Each cutting element comprises a feeler rod 116 having a horizontal part 118 and a vertical part or shank 120. The horizontal part rides upon or close to the exposed face of the fabric and has a tapered end face 122 terminated in an edge 124 which can pass under the floating sections 126. A thin knife blade 128 75

is fixed to the feeler rod and has an inclined cutting edge 130 merging into the inclined face 122 of the feeler rod. In this modification, since the floating threads lie parallel with the direction 5 of movement of the fabric, the cutter mechanism is adapted to be reciprocated at right angles to the line of fabric movement to sever the floating threads. Thus the horizontal section of the feeler rod is moved under the floating threads 10 which raises them into loop form and carries them onto the knife where they are severed.

The vertical part or shank 120 of the feeler rod is secured in a vertically and angularly adjustable manner by a set screw 132 in a chordal passage 15 of a supporting collar 134 which is angularly adjustable and axially movable on one or another of the bars 110, 112 and is clamped in any adjusted position on the bar by the set screw 136. The bars are provided with as many cutter elements as there are floating sections to the 20 fabric.

The ends of the bars are secured to brackets 138 which are secured to end frames 140 and 142, the brackets being adjustable toward and away 25 from each other on said frames to adjust the spacing between said bars in accordance with different dispositions of the floating threads and also to adjust accurately the line of severance of the floating sections. The end frames have rigidly fixed thereto pairs of outstanding guide rods 30 144 which are reciprocable in stationary bearings 146 and serve to guide the cutter elements for reciprocating movement.

The cutter elements are reciprocated in timed 35 relation to the web movement by means of a bell crank lever 148 pivoted at 150 to the frame and having one arm connected through a link 152 with an end frame 140. The other arm of the bell crank lever is connected through a safety 40 spring 154 with a flexible strap or cable 166 which passes around sheaves 158 and 160 and is connected to a jack lever 162, the reciprocation of which is under control of a pattern chain 164.

The pattern chain is provided with a pair of 45 projecting studs 166 and 168 of which the stud 166 effects the reciprocation of the jack lever in a direction to sever the floating strands and the stud 168 acts to hold the cutting elements for a short time in their forward cutting position 50 to more perfectly execute the complete cutting of the floating strands. The jack lever moves automatically to its initial position when free from control by the studs. A tensile spring 170 connected with the end frames 142 and with 55 a stationary part of the loom serves to effect the retraction of the cutting elements.

With both mechanisms above described the floating sections may be cut capable of being 60 formed into tufts very accurately and with little waste and during the weaving of the fabric and without adding appreciably to the cost of operation of the loom. The apparatus is simple and can be applied to almost any loom at small expense.

65 We claim:

1. The process of producing tufted woven fabric which includes the steps of weaving the fabric with floating filler threads interposed between the regular filling threads, stopping the take-up

of the fabric during the introduction of the floating threads, and severing the floating sections of the floating threads during the weaving operation.

2. The process of producing tufted woven fabric which includes the steps of weaving the fabric with warp and filler threads, at times inserting a plurality of floating threads between consecutive filling threads, interweaving the floating threads with selected warp threads while the fabric is stationary to bunch the floating threads, and severing the floating sections of the floating threads during the progress of weaving. 10

3. In a loom for weaving tufted fabric comprising fabric take-up mechanism, a plurality of 15 shuttles one containing a floating thread, means responsive to the service position of the floating thread shuttle for stopping the operation of said take-up mechanism, means for weaving the floating thread into the fabric to form floating thread 20 sections on a face thereof while the take-up mechanism is inoperative, and a plurality of cutter elements confronting a face of the woven fabric adapted to be engaged by the floating 25 thread sections to cut said sections as the fabric advances.

4. In a loom for weaving tufted fabric, a fabric take-up mechanism, reversing mechanism for the take-up mechanism, a plurality of shuttles 30 one containing a floating thread, means for weaving the floating thread into the fabric to form floating sections on a face thereof, means responsive to the service positioning of said floating thread shuttle for conditioning said reversing 35 mechanism to stop the operation of said take-up mechanism, and cutter elements located over the woven fabric for cutting the floating thread sections. 55

5. In a loom for weaving tufted fabric, take-up mechanism for the woven fabric, reversing mechanism for the take-up mechanism, a reversing arm for controlling said reversing mechanism, a plurality of shuttles one containing a floating thread, means for weaving the floating thread 40 into the fabric to form floating sections on one face of the fabric, means responsive to the active position of the floating thread shuttle for effecting operation of said reversing mechanism independently of said reversing arm to effect the 45 stopping of said take-up mechanism, and cutter elements located over the woven fabric for cutting the floating thread sections. 50

6. In a loom for weaving tufted fabric, take-up mechanism for the woven fabric, reversing mechanism for the take-up mechanism, a plurality of 55 shuttles one containing a floating thread, means for weaving the floating thread into the fabric to form floating sections on a face thereof, a shuttle chain movable to position the shuttles into active and inactive positions, means responsive to the movement of said chain into a position rendering said filling thread shuttle active to effect control of said reversing mechanism to stop said take-up mechanism, and cutter elements located over the woven fabric for cutting 60 the floating thread sections. 65
